UNITED STATES PATENT OFFICE.

HENRY FROELICH, OF LIHUE, TERRITORY OF HAWAII.

CANE-CARRIER FOR SUGAR-MILLS.

SPECIFICATION forming part of Letters Patent No. 781,511, dated January 31, 1905.

Application filed August 22, 1903. Serial No. 170,436.

To all whom it may concern:

Be it known that I, HENRY FROELICH, a citizen of the United States, and a resident of Lihue, in the Island of Kauai and Territory of Hawaii, have invented a new and Improved Cane-Carrier for Sugar-Mills, of which the following is a full, clear, and exact description.

My invention relates to cane-carriers for sugar-mills, my more particular object being to cause a uniform and even feed of cane to the crusher, thereby dispensing to a great extent with the necessity of manipulating the cane by hand.

My invention further relates to certain details of mechanism whereby the deposit of the cane upon the carriers is effected uniformly and automatically and whereby the distribution of the cane after reaching the carriers and before reaching the crushers is rendered as uniform as possible.

Reference is to be had to the accompanying drawings, forming a part of this specification, in which similar characters of reference indicate corresponding parts in all the figures.

Figure 1 is a side elevation showing my invention as applied to a sugar-mill. Fig. 2 is a fragmentary side elevation somewhat enlarged, but otherwise similar to the view shown in Fig. 1. Fig. 3 is a partial vertical cross-section upon the line 3-3 of Fig. 2. Fig. 4 is a vertical cross-section upon the line 4-4 of Fig. 2. Fig. 5 is a fragmentary perspective view showing my improved mechanism for maintaining the cane-car upon its track while being dumped. Fig. 6 is a fragmentary plan of the belt 32 and its connections, and Fig. 7 is a fragmentary perspective view of the adjustable limiting-stop for the belt 32.

Upon a suitable foundation 1 a crusher 2 is mounted in the usual manner, and this crusher is provided with rolls 3. A chute 4 is provided for feeding the cane downwardly and into the crusher. The outer end of the chute 4, together with the many working parts, is mounted upon the framework 5. The crusher is driven in any approved manner, and this part of the mechanism being old needs no description. By means of a sprocket-chain 6 power is conveyed from the crusher to the rollers 7, which drive the endless traveling

apron 8. This apron is provided with bearings 8^a, which rest upon the rolls 9, thereby relieving friction to as great an extent as possible. Connected with a toothed wheel 10 and driven thereby is a gearing 11, from which is driven a sprocket-chain 12, this sprocket-chain causing the rotation of a shaft 13, provided with knives 14. The arrangement of the gearing is such that the knives 14 have a higher speed in the same direction than the upper portion of the endless carrier 8. A take-up 15, provided with a screw 16, serves to tighten or loosen the driven belt or carrier 8. A second endless belt or carrier 17 is so mounted as to be free to travel upon the rollers 18 and is provided with fingers 19, preferably of the shape indicated. This belt or carrier is mounted upon the cylinders 20 21, the latter cylinder being connected with a take-up 22, provided with an adjusting-screw 70 23. The carrier 17 is propelled by means of a sprocket-chain 24, which engages a sprocket-wheel 25 upon the shaft 26. By means of a sprocket-chain 27 motion is communicated to the revolute cylinder 28. Connected with 75 the shaft 30 of this cylinder, which forms a pivotal support, is a frame comprising bars 29, and upon the outer or free end of this frame is a revolute cylinder 31. An endless belt or carrier 32 extends from the revolute cylinder 80 28 to the revolute cylinder 31. Mounted upon this belt 32 are fingers 33 and knives 34. A take-up 35, provided with an adjusting-screw 38^a, is used for the purpose of adjusting the tension of the belt 32. An arc-shaped guide 85 36 is provided with a slot 37, and slidably mounted upon this guide is a limiting-stop 38, provided with a thumb-nut 39, whereby the limiting-stop may be placed in any desired position relatively to the slot 37—that is to say, 90 the limiting-stop may be moved upward within the slot 37 by merely loosening the thumb-nut 39, pushing the limiting-stop 38 upward to the point desired, and tightening the thumb-nut 39. By this means the bars 29 may be given 95 any desired degree of inclination.

A platform 40 is mounted upon trunnions 41 and is provided with a lever 42 and a brace 43, as shown more particularly in Fig. 3. Upon the lower end of the lever 42 is an iron 100

hood 44, which is engaged by a chain 45. This chain passes over pulleys 46 47 48 and chain-wheel 49 and is thereby connected with a gearing 50, controllable by a hand-wheel 51. It will be seen from Fig. 3 that by turning the hand-wheel 51 to the right or to the left the lever 42 may at will be drawn from its position shown in full lines to that shown in dotted lines. The platform 40 is provided with rails 52, upon which the cane-car 53 is supported. Mounted upon the side of the car 53 is a cleat 54. This cleat is detachably engaged by a hook 55, provided with a turnbuckle 56 and revolute head 57, mounted upon the shaft 58, which rests in bearings 59. The shaft 58 is provided with a fork 60, which may be turned within certain limits by lowering the hook 55 to a substantially horizontal position. A hasp 61 is secured fixedly in position by means of bolts 62. When the operator desires to dump cane from the car 53, he raises the hook into the position indicated in Figs. 3 and 5, thereby causing the hook to engage the cleat 54. By manipulating the hand-wheel as above described the car may be dumped, as indicated by dotted lines in Fig. 3. The hook 55 by binding firmly upon the cleat 54 prevents the car from leaving the rail. The car being dumped and restored to the position indicated in full lines in Fig. 3, the hook 55 is detached from the cleat and is lowered to a horizontal position, thereby causing the fork 60 to assume a vertical position, one of the forks, 60^a, being thereby carried directly beneath the hasp 61 and preventing the platform 40 from being tilted at an inopportune moment so as to dump the car. The hasp 61 is mounted upon a stationary flooring 63. A fender 64 depends from the platform, and a bevel 66 is provided for the purpose of facilitating the sliding of the cane downward upon the carrier 17. The door of the car is shown at 65 and also constitutes an inclined surface over which the cane may travel freely. If desired, however, the car 53 need not be used for dumping the cane, which step may be performed by hand or by an unloading-machine.

It will be seen from Fig. 4 that the traveling apron 17 is somewhat broader than the traveling apron 8. By this means the distribution of the cane is rendered somewhat more effective, because as the cane passes from the upper apron to the lower one the tendency is to make the layer of the cane slightly deeper upon the lower traveling apron. It will be also noted that the guard 67, which is provided with notches 68, serves as a fender for preventing the cane from being drawn out beneath the endless apron 17. A somewhat similar guard is shown at 13^a. The purpose of this guard is to prevent cane from passing over the cutters 14. By its use cane is fed beneath the cutter. In all cases the cutters have a higher speed than the speed of the traveling cane.

The operation of my device is as follows: After the cane is dumped by hand or by an unloading-machine it is merely thrown evenly upon the carrier 17. If, however, it is desired to dump the cane by the mechanism described, the car 53 is moved out upon the rails 52, the hook 55 is placed upon the cleat 54, and the hand-wheel 51 is manipulated for the purpose of dumping the cane upon the carrier 17. This manipulation dispenses with all the laborers heretofore used on the carrier and unloading-machines. Of course some care must be exercised in manipulating the hand-wheel 51, so that the cane is dumped with considerable uniformity. The fingers 19, together with the motion of the carrier 17, tends to distribute the cane still more equally. The cane is now carried up the incline represented by the upper surface of the carrier 17, and any excess of cane resting upon the carrier is vigorously manipulated by the fingers 33 upon the belt 32 and also by the knives 34 upon this belt. The fingers 33 and knives 34 have a motion contrary to that of the belt 17 and also have greater rapidity. Should a large mass of cane chance to lodge upon any given portion of the carrier 17, the mass upon reaching the outer or free end of the belt 32 and being operated upon by the fingers and knives 33 34 is thrown backward, and thus partially scattered down the inclined surface of the carrier 17. Normally this is all that occurs in case of a large pile of cane coming up at the same time to the fingers and knives. Occasionally it may happen, however, when such a gorge of cane occurs that the fingers and knives are unable to scatter the accumulation, and in this event the mass of cane causes the roller 31 to be lifted bodily, thereby preventing breakage of the knives and fingers and allowing the excess of cane to pass. The cane passes from the upper or left-hand end of the carrier 17 to the lower end of the carrier-belt 8, from which it is conveyed upward to the chute 4. Just before passing into the chute, however, the cane is subjected to a second manipulation by the revolute knives 14, which travel in the same direction to that of the cane and render the distribution of the cane still more effective. It will be understood, of course, that all of the knives used have a sufficient speed to cut projecting stalks of cane and that independently of their cutting function they serve as distributors. The cane next passes into the chute 4, entering at the larger upper end thereof, and is thus delivered to the crusher.

Having thus described my invention, I claim as new and desire to secure by Letters Patent—

1. The combination of a traveling endless apron, a frame mounted adjacent thereto and free to swing, a belt movable relatively to said frame, knives mounted upon said belt, and means for actuating said belt.
2. In a cane-carrier for sugar-mills, the com-

5 combination of a member for conveying cane from one point to another, a frame mounted thereover and free to swing relatively thereto, revolute members mounted upon said frame, 5 means for actuating said revolute members, a belt mounted upon said revolute members and driven thereby, and knives mounted upon said belt and provided with edges directed against the flow of the cane.

10 3. In a cane-carrier for sugar-mills, the combination of an endless traveling apron, means for actuating the same, mechanism mounted adjacent to said endless traveling apron and provided with knives having edges disposed 15 in a direction opposite the general direction of travel of said apron for the purpose of mutilating cane resting thereupon, and means for automatically allowing said mechanism to move relatively to said apron under the pressure 20 of an excess of said cane.

4. In a cane-carrier for sugar-mills, the combination of a member for conveying cane from one point to another, mechanism provided with active members for mutilating said cane, said 25 mechanism being free to swing, means for actuating said mechanism so that said members travel in a direction contrary to that of said cane, and a limiting-stop controllable at will for governing the amount of swing of said 30 mechanism.

5. In a cane-carrier for sugar-mills, the combination of an endless traveling apron, a belt mounted thereover, cutting-knives mounted upon said belt for the purpose of mutilating 35 the cane resting thereupon and also for exerting a raking action upon the cane, said knives being provided with edges directed contrary to the general direction of travel of

40 said cane, fingers mounted upon said belt intermediate of said cutting-knives and also adapted to exert a raking action upon the cane, and means for actuating said endless traveling apron and said belt.

6. In a cane-carrier for sugar-mills, the combination of an endless traveling apron, a belt 45 mounted thereover, cutting-knives mounted upon said belt for the purpose of mutilating the cane resting thereupon and also of exerting a raking action upon the cane, said knives being provided with edges directed contrary to the general direction of travel 50 of said cane, and means for actuating said endless traveling apron and said belt.

7. In a cane-carrier for sugar-mills, the combination of mechanism for conveying the cane from one point to another, a table disposed adjacent to said mechanism and free to tilt relatively thereto, a vehicle mounted upon said table and free to receive and discharge cane relatively to said mechanism for conveying the same, means controllable at will for causing said table to tilt, a shaft journaled upon said table, a hook connected with said shaft and adapted to engage said vehicle for holding the same upon said table, while said table is tilted, a fork connected with said shaft and free to turn therewith, and a stationary fastening for engaging said fork and temporarily preventing said table from tilting.

In testimony whereof I have signed my name to this specification in the presence of two subscribing witnesses.
